MULTIFINAL ELEMENT SINGLE MASTER CONTROL SERVOSYSTEM

This is a divisional application of my copending application Ser. No. 595,399, filed Nov. 18, 1966 and now U.S. Pat. No. 3,469,354 issued Sept. 30, 1969. This invention relates to a servosystem and more particularly to an electrical servosystem for moving and positioning a plurality of movable devices or accessories one at a time and independently of each other.

Typically, as in buildings designed to accommodate at various times a large variety of types of activities hereinafter referred to as "multiple-use building" such as an auditorium, it has been proposed that the acoustical, lighting and/or other characteristics of such buildings or auditoriums be varied for optimum performance of the activity by providing movable accessories at strategic points about the building. For example, multiple and diverse lights, including movable flood and spot lights, are commonly used. Also, movable acoustical members, such as panels, curtains and the like, and movable microphones are frequently utilized to vary the acoustical characteristics of such buildings.

While these movable accessories have materially increased the quality of the characteristics of such buildings for the various types of activities taking place therein, the same have many serious deficiencies, particularly in the proper positioning thereof for optimum utilization thereof for the various activities. In this respect, it has been conventional practice to rely solely upon manual positioning of these accessories to approximate positions thought to provide the desired characteristics. Such manual positioning is inefficient and most often inaccurate, and thereby results in less than optimum settings of the accessories.

Attempts have heretofore been made to mechanize some of these movable accessories such as acoustical accessories and two general types of controls have been provided therefor. The most common of which is a gang type of control wherein a group of the accessories are interconnected and move as a unit, and the second is an individual control for each accessory. In each instance, the controls are located at a central control point remote from the accessories.

While such mechanization provides decided advantages over the aforementioned manual positioning of the accessories such controls have serious limitations which have limited their acceptance and use. For example, with the gang control, it is not possible to adjustably control the positional relationship between accessories in a group and hence considerable flexibility in the variance of the characteristics of the building is lost. The individual controls, while permitting each accessory to be positioned independently, still relies upon the skill and knowledge of the operator, and is subject to his errors in judgment and manipulation of the accessories and therefore does not permit the variance of the characteristics of the building to be fully exploited. Further, it requires a large control unit, and therefore a large amount of space at the control point, which is very expensive.

It is therefore an object of the present invention to provide a servosystem for independently controlling the positioning of each of a plurality of movable accessories wherein the desired position for each accessory is accurately controlled in accordance therewith.

Another object of this invention is to provide in combination with a plurality of movable accessories, each movable to a plurality of positions, a servosystem for accurately positioning each of the accessories one at a time and independently of each other into a predetermined positional relationship. Some of the objects of the invention having been stated, other objects will appear as the description proceeds when taken in connection with the accompanying drawings, in which:

FIG. 1 is a diagrammatic perspective view of a building provided with a plurality of movable accessories for varying the characteristics of the building;

FIG. 2 is a functional schematic view of a portion of a servosystem for controllably varying the position of the movable accessories;

FIG. 3 is a schematic electrical diagram, showing a preferred electrical relationship of all the elements of a servosystem according to the invention;

FIG. 4 is an electrical wiring diagram showing those components within the control unit in the lower left-hand portion of FIG. 2;

FIG. 5 is an electrical wiring diagram of one of the control stations for a plurality of slave units shown in FIG. 2; and

FIG. 6 is a schematic view of the internal wiring of one of the slave units in the control station of FIG. 5. Referring more specifically to the drawings, a multiple-use building, generally designated at 10, is shown in FIG. 1 as one environment in which the servosystem of the present invention may be used. Building 10 has a performance area or stage 11 adapted for the performance of a variety of activities and an audience area or auditorium 12 adapted to contain or seat an audience for the presentation of the featured activity. Building 10 is provided with a plurality of accessories mounted for movement relative to building 10 to vary the acoustical, lighting and/or other characteristics of the building for optimum performance and enjoyment of each type of activity performed therein. Various types of movable accessories which may be provided in the building 10 are disclosed in greater detail in my aforementioned U.S. Pat. No. 3,469,354 and the disclosure of such movable accessories is herein incorporated by reference from that patent.

The present invention provides a servosystem for controllably moving each of the movable accessories into any respective desired positioned relationship with the building 10 to vary the characteristics of the building to be optimum for the performance of each particular activity. While this servosystem is shown and will be described in connection with the above described building and accessories, it should be understood that the same is not restricted thereto, but may be used to selectively controllably move or position any plurality of movable devices or accessories one at a time and independently of each other.

This servosystem includes an individual slave unit 31 (FIG. 40) for controlling the movement of each individual accessory and additionally, individual slave units 31 are provided for controlling each type of movement of an accessory having more than one type of movement. Each slave unit 31 includes a motive means for moving the corresponding movable accessory to its various positions and which preferably is in the form of an electric motor 33 and speed reduction means connecting the output of electric motor 33 to the corresponding movable accessory.

Preferably, electric motor 33 is of the reversible type having a forward direction circuit or winding 33a and a reverse direction circuit or winding 33b (FIG. 6) for moving the corresponding accessory in either of two directions as determined by the particular winding energized. The transmission of rotation from such an electric motor 33 to a movable accessory is disclosed more fully in my aforementioned U. S. Pat. No. 3,469,354, to which reference is made for additional details of disclosure. Each slave unit 31 also includes a slave reference device 40 which preferably is in the form of a slave variable resistor 41 (FIG. 6) having a positionally movable member 42 for varying the resistance thereof. The positionally movable member 42 of slave variable resistor 41 has a predetermined range of movement, and a feedback means F connects this positionally movable member 42 to the corresponding accessory for correlated movement of the positionally movable member therewith. Therefore, the positionally movable member 42, by its position, will indicate the corresponding position of the accessory to which it is connected. Preferably, feedback means F comprises a gear train which connects the positionally movable member 42 to the corresponding accessory in such a manner that the positionally movable member 42 moves throughout its full range of movement. In this respect, limit switches 43, 44 (FIG. 6) are provided and are associated with an actuator means 45 which is connected to and moves with the positionally movable member 42. These limit

50 55 60 65 70 75

Preferably, electric motor 33 is of the reversible type having a forward direction circuit or winding 33a and a reverse direction circuit or winding 33b (FIG. 6) for moving the corresponding accessory in either of two directions as determined by the particular winding energized. The transmission of rotation from such an electric motor 33 to a movable accessory is disclosed more fully in my aforementioned U. S. Pat. No. 3,469,354, to which reference is made for additional details of disclosure. Each slave unit 31 also includes a slave reference device 40 which preferably is in the form of a slave variable resistor 41 (FIG. 6) having a positionally movable member 42 for varying the resistance thereof. The positionally movable member 42 of slave variable resistor 41 has a predetermined range of movement, and a feedback means F connects this positionally movable member 42 to the corresponding accessory for correlated movement of the positionally movable member therewith. Therefore, the positionally movable member 42, by its position, will indicate the corresponding position of the accessory to which it is connected. Preferably, feedback means F comprises a gear train which connects the positionally movable member 42 to the corresponding accessory in such a manner that the positionally movable member 42 moves throughout its full range of movement. In this respect, limit switches 43, 44 (FIG. 6) are provided and are associated with an actuator means 45 which is connected to and moves with the positionally movable member 42. These limit

switches 43, 44 are connected to the electric motor 33 by suitable wiring and are located at positions corresponding to the limits of the range of movement of the positionally movable member 42 to stop motor 33 when positionally movable member 42 reaches the limits of its range of movement. Therefore, limit switches 43, 44 define the limits of the range of movement of the accessory being moved by the motor 33.

Conveniently, slave units 31 for a plurality of functionally similar accessories may be interconnected into a slave station broadly designated for control of that function. For example, as seen in FIG. 2, all of the slave units 31 for raising and lowering the overhead stage panel 22 are interconnected into a slave station 50, while all of the slave units 31 for tilting the left side stage panels 20 are interconnected into a slave station 51. Similar slave stations 52, 53, 54, 55, 56, 57, 58 and 59 are provided for other groups of slave units for controlling various groups of accessories as indicated by the legends in FIG. 2.

This interconnection of a plurality of slave units 31 into a slave station is illustrated schematically in FIG. 14 and for convenience of illustration only, each such slave station has been shown as including four slave units 31 but it is apparent that the same could include more or less slave units as desired. Each slave station, as for example slave station 50, is shown as being a female contact board having contacts 50a and 50b connected to a source of AC electrical power. Contact 50b is connected by suitable wiring to the winding circuits of the electric motor 33 of each slave unit 31. Contacts 50c, 50d, 50e, 50f, 50g, 50h, 50k, 50m; and 50n, 50n, 50p, 50r are respectively connected to the winding circuits of motor 33 and positionally movable member 42 of the slave units 31. Contact 50s is connected to the slave variable resistor 41 of each slave unit 31.

For individually and independently controlling the movement and positioning of each of the movable accessories, the servosystem of the present invention further includes a master control unit 60 FIGS. 2 and 4) which may be selectively electrically connected to any one of the slave stations 50 through 59. While a cannon plug type connection 61 having contacts 61a, 61b, 61c, 61d, 61e, 61f, 61g, 61h, 61i, 61k, 61m, 61n, 61p, 61r and 61s corresponding to the contacts of the slave stations is shown, it should be understood that any other type of selective interconnection between the master control unit 60 and a selected slave station may be utilized, such as a multipole, multithrow selector switch (not shown).

Master control unit 60 includes a master control device 62 having a positionally adjustable member 63 movable through a predetermined range of movement and having the various positions to which the same may be adjusted correlated to the various positions to which the accessories are movable. Preferably, master control device 62 comprises a master variable resistor 64 having the positionally adjustable member 63 as the wiper arm thereon for varying the resistance thereof.

Master control unit 60 also includes selector means for selectively electrically interconnecting each of the slave reference devices 40 of the slave units 31 connected into a selected slave station to the master control device 62, one at a time and independently of each other. This means preferably is in the form of a multipole, multiposition selector switch 65 which is illustrated in the drawing as having four poles or sections 65a, 65b, 65c and 65d with each section having five positions numbered 0, 1, 2, 3 and 4. The positions 1, 2, 3 and 4 of switch section 65a are electrically connected by suitable wiring to the positionally movable members 42 of the various slave reference devices 40 connected in the selected slave station. Of course, if more or less slave units were connected in the slave station, the number of positions of the sections of selector switch 65 will be varied accordingly.

The selector switch section 65b has the position 1, 2, 3 and 4 thereof respectively connected by suitable wiring to the forward and reverse direction windings of the electric motors 33 of the slave units 31. The other selector switch sections 65c and 65d are for control of the slave units separate and apart from the master control device 62 and will be described hereinafter.

Master control unit 60 also includes means for generating an electrical signal in response to a deviation of the positionally movable member 42 of a selected slave reference device 40 connected to the master control device 62 from a predetermined correlated positional relationship with the positionally adjustable member 63 of master control device 62. Preferably, this signal generating means is an electrical comparison circuit for comparing the resistances of the master variable resistor 64 and the slave variable resistor 41 of the selected slave reference device 40. This comparison circuit preferably is a wheatstone bridge circuit 66 which has the master variable resistor 64 connected in a side 66a and the selector switch 65 and selected slave variable resistor 41 connected in the electrically opposite side 66b thereof. The remaining sides 66c and 66d have standard matched resistors 67, 68 connected therein.

The wheatstone bridge circuit 66 is preferably DC energized across a first pair of opposite corners 66e and 66f and therefore, these corners are connected by suitable wiring to a standard source of AC power through a bridge rectifier 69 and a suitable transformer 70. Accordingly, upon an imbalance between the resistance of the master variable resistor 64 and that of the selected slave variable resistor 41 due to a deviation from the predetermined positional relationship of the positionally adjustable wiper member 63 of the master variable resistor 64 with the positionally movable member 42 of the slave variable resistor 41, an electrical signal will be generated across the other two opposite corners 66g and 66h of the wheatstone bridge circuit 66.

In accordance with the present invention, means is connected to the wheatstone bridge circuit 66 and to the electric motors 33 of the slave units 31 for energizing the electric motor 33 of the selected slave unit 31 in response to the generated electrical signal. Preferably, this means is polarized so as to energize the appropriate winding of the electric motor 33 to cause the same to move the accessory connected thereto in a direction, corresponding to the polarity of the generated signal, to move the accessory and the positionally movable member 42 of the selected slave reference device 40 into the predetermined positional relationship with the wiper member 63 of the master slave resistor 64 by the shortest available path.

As illustrated in the drawings, this means comprises a pair of relays 71, 72 connected in parallel across the opposite corners 66g and 66h and polarized by the appropriate use of diodes. Relay 71 has its contacts 71a, 71b, 71c and 71d connected in series in the forward direction windings 33a of the electric motors 33, and relay 72 has its contacts 72a, 72b, 72c and 72d connected in the reverse direction windings 33b of the electric motors 33.

Master control unit 60 includes a control panel 73 having a control knob 74 connected to the positionally adjustable member 63 of master control device 62 for manual movement and positioning thereof. To aid in this positioning, a pointer 75 is connected to and moves with knob 74 and cooperates with a dial 76 having three calibrated scales 76a, 76b and 76c thereon. Scales 76a and 76c are calibrated in degrees and correspond to the range of tiltable movement of the panels 20, 21, 22, 23, 24 and 25, and scale 76b is calibrated in feet and corresponds to the vertical range of movement of the overhead stage panels 22 and the light means 13, microphone means 14 and drop curtains 26.

Control panel 73 also includes a control knob 77 connected to the poles of selector switch 65 for manual movement thereof to select the particular slave unit to be connected to the master control device 62. To aid in this selection, a pointer 78 is carried by knob 77 and moves therewith and cooperates with a dial 79 having five positions corresponding to the five positions of selector switch 65.

Preferably, suitable override means is provided in control unit 60 for permitting manual overriding control of the slave units 31 separate from the master control device 62. In this respect, the positions 1 through 4 of selector switch section 75 65c are respectively connected by suitable wiring to the for-

ward direction windings 33a of the electric motors 33 and the corresponding positions of selector switch section 65d are connected to the reverse direction windings of the electric motors 33. A double-throw manual selector switch 80 has one contact 81 thereof connected to the selector switch section 65c and the other contact 82 thereof connected to the selector switch section 65d. By appropriate movement of the switch 80 to its two active positions, forward or rearward rotation of the motors 33 may be provided in overriding relation to the master control device 62. It is noted that if the selector switch 65 is dialed to a selected slave unit and the manual override switch 80 is actuated to cause the motor 33 of that slave unit to move the accessory to a particular desired position, that when the manual override switch 80 is released the master control device 62 will attempt to cause the accessory to move into the predetermined positional relationship therewith; therefore the selector switch 65 must be moved to the "zero" or off position if the accessory is to be retained in the position to which it was moved by the override control.

A gang control mechanism is preferably included in the master control unit 60 to permit optional gang movement of all accessories connected to a slave station. In this respect, a gang switch 83 (FIGS. 2 and 3) has a first series of contacts 83a-83d thereof connected to the reverse direction windings 33b of each of the motors 33, and another series of contacts 83e-83f thereof connected to the forward direction windings 33a thereof. Gang switch 83 has each series of contacts thereof connected in series with the forward and reverse contacts 81 and 82 of the manual override switch 80, and can only be used in conjunction therewith. Additionally, to achieve gang control of all of the motors, the selector switch 65 should be moved to the "zero" or off position before gang switch 83 is actuated.

Preferably, control unit 60 includes an indicator light 84 FIGS. 2 and 3) switch is connected in the polarized relay circuit so as to be lighted upon the generation of an electrical signal of either polarity, and to be unlighted when no signal is generated, as when the positionally adjustable member 63 of the master variable resistor 64 is in the predetermined positional relationship with the positionally movable member 42 of the slave variable resistor 41.

The operation of the servosystem of the present invention in the positioning of the movable accessories will now be described. When the position of any one or more of the accessories corresponding to one of the slave stations 50-59 is to be adjusted, the master control unit 60 is connected to the appropriate slave station. The desired position of the accessory is then preset or predetermined by manually rotating control knob 74 until pointer 75 is in a position relative to the appropriate scale corresponding to the desired position of the accessory. This moves the positionally adjustable member 63 of the master variable resistor 64 into a corresponding position and causes master variable resistor 64 to have a correlated resistance. Then, the slave unit 31 corresponding to the accessory to be positioned is connected to master control device 62 by moving the selector switch 65 to the appropriate position by means of control knob 77. Thereby, the slave variable resistor 41 of the selected slave unit 31 is placed in resistance-comparison relationship with the master variable resistor 64 across the wheatstone bridge circuit 66.

Due to the manual adjustment of the positionally adjustable wiper member 63 to the desired position of the accessory, there will probably be a resistance imbalance across the wheatstone bridge, and an electrical signal of a polarity corresponding to a direction opposite to the direction of the deviation will be generated. The appropriate one of the polarized relays 71 or 72 will be energized by the electrical signal and will in turn energize the appropriate winding of the electric motor 33 of the selected slave unit 31 to move the accessory in a direction to bring it to its desired position by the shortest available path of travel. As the accessory is moved, the positionally movable member 42 of the selected slave variable resistor 41 will be moved with the accessory, due to the

feedback means F interconnecting the same, until the positionally movable member 42 of the slave variable resistor 41 is brought into predetermined correlated positional relationship with the positionally adjustable member 63 of the master variable resistor 64 and until the slave variable resistor 41 is brought into resistance balance with the master variable resistor 64 across the bridge. When this occurs, the generated electrical signal will terminate and the relay will open. The electric motor 33 of the selected slave unit 31 will be deenergized and will terminate movement of the accessory and maintain the same in the position to which it has been moved.

It is noted that during movement of the accessory the light 84 will be lighted, and that immediately upon its becoming unlighted when the circuit to the motor 33 is open, the operator will know that he may select another accessory through the selector switch 65 for positional adjustment. As stated earlier, the operation of the master control device may be overridden by the manual override switch 80 alone or in combination with the gang control switch 83.

The control unit 60 may be suitable disconnected from the particular slave station when each of the accessories corresponding to that slave station have been moved to the desired position, and may be connected to any one or successively to all of the remaining slave stations for appropriate positioning of other accessories. It should be noted that, due to the construction of the control unit 60 and the slave units 31, the adjustment of the accessories may occur at any time including during the performance of a particular activity without distracting the audience or performers. Additionally, because the particular position of any accessory may be preset or predetermined by the position of the positionally adjustable member 63 of the master control device 62, the optimum positions of such accessories for each type of activity may be very accurately predetermined prior to the performance of the activity, as for example during a rehearsal, and the accessories moved to their optimum positions for the particular activity in a minimum time and with minimum expense and great accuracy. Additionally, the positions of the accessories may be adjusted for variance in building characteristic requirements occurring during the performance of the particular activity, unnoticeably and with great precision.

It is therefore believed apparent that the present invention provides a novel servosystem for controlling the movement and positioning of a plurality of accessories, one at a time and independently of each other, and with great accuracy and precision. While the servosystem of the present invention has been described in cooperation with a plurality of accessories for varying the characteristics of a multiple use building such as an auditorium, it will be readily apparent that the servosystem may be used in cooperation with any type accessories wherein the accessories are each movable to a plurality of positions.

In the drawings and specification there has been set forth a preferred embodiment of the invention and, although specific terms are employed, they are used in a generic and descriptive sense only and not for purposes of limitation.

I claim:

1. An electrical servosystem for use with a plurality of accessories each movable to various positions within a range of positions and comprising:

a plurality of motive means each adapted to be operatively connected to a corresponding one of the accessories for moving the same to various positions within a predetermined range of positions,

a plurality of slave reference devices each having a positionally movable member operatively connected to a corresponding one of said motive means for correlated movement therewith as said corresponding one accessory is moved to various positions within said predetermined range of positions,

a single master control device having a positionally adjustable member infinitely variably movable over a predetermined range of adjustment,

position balancing electrical circuit means electrically connected to said master control device for responding to the relative position of said adjustable member within said predetermined range of adjustment and including switching means for controllably energizing said motive means, and

5 electrical switch selector means electrically connected to said position balancing electrical circuit means, to said master control device, to each of said slave reference devices and to each of said motive means for selectively electrically interconnecting each of the corresponding ones of said slave reference devices and said motive means, one pair at a time and independently any other pair, to said position balancing electrical circuit means and said master control device,

10 said position balancing circuit means and said master control device cooperating with a selected pair of a slave reference device and corresponding one motive means for generating an electrical signal in response to a deviation from a predetermined positional relationship between the positionally adjustable member of said master control device and the movable member of said selected slave reference device and for energizing said selected motive means to move the positionally movable member of said selected slave reference device into said predetermined correlated positional relationship.

15 2. A servosystem according to claim 1, wherein said master control device comprises a master variable resistor including said positionally adjustable member, said positionally adjustable member being effective to vary the resistance of said master variable resistor upon positional adjustment thereof, and wherein each of said slave reference devices comprises a slave variable resistor including said positionally movable member, said positionally movable member being effective to vary the resistance of said slave variable resistor upon positional movement thereof.

20 3. A servosystem according to Claim 2, wherein said means for generating said electrical signal comprises an electrical comparison circuit connecting said master variable resistor and said slave variable resistor of said selected slave reference device in resistance comparison relationship to generate said electrical signal in response to an imbalance between the resistance of said master variable resistor and the resistance of the slave variable resistor of said selected slave reference device due to a deviation from said predetermined positional relationship of said positionally adjustable member and said positionally movable member.

25 4. A servosystem according to claim 3, wherein said electrical comparison circuit comprises a wheatstone bridge, and wherein said means for energizing said motive means comprises relay means electrically connected to said wheatstone bridge to receive said generated electrical signal and electrically connected to said motive means for energizing the motive means corresponding to said selected slave reference device in response to said generated electrical signal.

30 5. A servosystem according to claim 4, wherein said wheatstone bridge is DC energized so that said generated electrical signal is of a polarity corresponding to the direction of movement required of the positionally movable member of said selected slave reference device to move the last-named member into said predetermined positional relationship with said positionally adjustable member of said master control device by the shortest available path, said plurality of motive means each comprising a reversible electric motor having a forward direction circuit and a reverse direction circuit, and said relay means being polarized so as to energize the forward or reverse direction circuit of the electric motor corresponding to said selected slave reference device in response to a generated electrical signal of the appropriate polarity, 65 whereby said last-named motor moves the positionally movable member of said selected slave reference device into said predetermined positional relationship with said positionally adjustable member of said master control device by the shortest available path.

6. A servosystem according to claim 5, wherein said relay means includes

a pair of relays electrically connected in parallel to each other and to said DC energized wheatstone bridge for receiving the polarized electrical signal generated thereby, one of said relays being electrically connected to said forward direction circuit of each of said reversible electric motors for energization thereof and the other of said relays being electrically connected to said reverse direction circuit of each of said reversible electric motors for energization thereof, and

10 diode means electrically associated with each of said relays for polarizing said relays to energize one of the forward and reverse direction circuits of the electric motor of the selected slave reference device in accordance with the polarity of the electrical signal generated by said wheatstone bridge to move the positionally movable member of the selected slave reference device into the positionally correlated position with the positionally adjustable member of the master reference device by the shortest available path.

15 7. The servosystem according to Claim 1 wherein said plurality of motive means each comprises

a reversible electric motor having a forward direction circuit and a reverse direction circuit, and wherein said energizing means for energizing said motive means includes

20 overriding selector switch means electrically connected to said forward and reverse direction circuits of each of said electric motors for selectively and directly electrically energizing one of the forward and reverse direction circuits of each of said motors one at a time and independently of each other to manually position the positionally movable member of the selected slave reference device and any accessory which may be connected thereto at any desired position independently of the master control device.

25 8. A servosystem according to claim 1 wherein said plurality of motive means each comprises

a reversible electric motor having a forward direction circuit and a reverse direction circuit, and wherein said energizing means includes

30 gang control switch means electrically connected to said forward and reverse direction circuits of each of said motors for selectively electrically interconnecting one of said forward and reverse direction circuits of all of said electric motors simultaneously to manually position the positionally movable member of all of said slave reference devices and the accessories which may be connected thereto at any desired position independently of the master control device.

35 9. A servosystem according to claim 1, including means electrically connected to said signal generating means and responsive to the electrical signal generated thereby for indicating whether said positionally movable member of said selected slave reference device is in predetermined positional relationship with said positionally adjustable member of said master control device.

40 10. In combination with a plurality of movable accessories, each movable to various positions within a range of positions, an electrical servosystem for accurately positioning each of the accessories one at a time and independently of other accessories and comprising:

a plurality of motive means each operatively connected to a corresponding one of the accessories for moving the same to various positions within a predetermined range of positions,

45 a plurality of slave reference devices each having a positionally movable member operatively connected to a corresponding one of said motive means for correlated movement therewith as said corresponding one accessory is moved to various positions within said predetermined range of positions,

a single master control device having a positionably adjustable member infinitely variably movable over a predetermined range of adjustment, position balancing electrical circuit means electrically connected to said master control device for responding to the relative position of said adjustable member within said predetermined range of adjustment and including switching means for controllably energizing said motive means, and electrical switch selector means electrically connected to said position balancing electrical circuit means, to said master control device, to each of said slave reference devices and to each of said motive means for selectively electrically interconnecting each of the corresponding ones of said slave reference devices and said motive means, one pair at a time and independently any other pair, to said position balancing electrical circuit means and said master control device, said position balancing circuit means and said master control device cooperating with a selected pair of a slave reference device and corresponding one motive means for generating an electrical signal in response to a deviation from a predetermined positional relationship between the positionably adjustable member of said master control device and the movable member of said selected slave reference device and for energizing said selected motive means to move the positionably movable member of said selected slave reference device into said predetermined correlated positional relationship.

11. The combination according to claim 10, wherein said

master control device comprising a master variable resistor including said positionally adjustable member, said positionally adjustable member being effective to vary the resistance of said master variable resistor upon positional adjustment thereof and wherein each of said slave reference devices comprises a slave variable resistor including said positionally movable member, said positionally movable member effective to vary the resistance of said slave resistor upon positional movement thereof.

10 12. The combination according to claim 11, wherein said means for generating said electrical signal comprises an electrical comparison circuit connecting said master variable resistor and said slave variable resistor of said selected slave reference device in resistance comparison relationship to generate said electrical signal in response to an imbalance between the resistance of said master variable resistor and the resistance of the slave variable resistor of said selected slave reference device due to a deviation from said predetermined positional relationship of said positionally adjustable member and said positionally movable member.

15 13. The combination according to claim 10 wherein each of said motive means comprises a reversible electric motor having forward and reverse direction circuits, and wherein said energizing means includes means for energizing the appropriate one of said forward and reverse direction circuits of the electric motor connected to the selected slave reference device for moving the accessory into the predetermined positional relationship with the positionally adjustable member of the master control device by the shortest available path.

UNITED STATES PATENT OFFICE
CERTIFICATE OF CORRECTION

Patent No. 3,586,952 Dated June 22, 1971

Inventor(s) Grover C. Meetze, Jr.

It is certified that error appears in the above-identified patent and that said Letters Patent are hereby corrected as shown below:

In title change "MULTIFINAL" to --MULTI-FINAL--; change "SERVOSYSTEM" to --SERVO-SYSTEM--;

In References Cited, change the proper name "Kickinson" to --Dickinson--;

In the specification, change every instance of "servosystem" to --servo-system--;

Column 3, line 12, change "panel" to --panels--;
line 28, before "50k" insert --50i--; same line, after "and"
delete --50n-- (first occurrence);
line 36, after the numeral "60" and before "FIGS", insert
-- (--;
line 69, change "position" to --positions--;

Column 4, line 60, change the numeral "766" to --76b--;

Column 5, line 24, change "83a-83" to --83a-83d--;
line 26, change "83e-83" to --83e-83h--;
line 36, change "switch" to --which--;

Column 6, line 20, change "suitable" to --suitably--;

Column 8, line 49, change "references" to --reference--.

Signed and sealed this 28th day of December 1971.
